UNITED STATES PATENT OFFICE.

JOHN W. COLGLAZIER, OF SPRINGFIELD, ILLINOIS.

AUTOMATIC TOY.

1,139,955.

Specification of Letters Patent. Patented May 18, 1915.

Application filed September 14, 1914. Serial No. 861,733.

To all whom it may concern:

Be it known that I, JOHN W. COLGLAZIER, a citizen of the United States, residing at Springfield, in the county of Sangamon and State of Illinois, have invented new and useful Improvements in Automatic Toys, of which the following is a specification.

My invention relates to mechanical toys, and applies more particularly to a novel form of automatic conveyer operated by weights, by which a miniature car may be hoisted, filled with sand, allowed to descend, and dumped, in a methodical and orderly manner.

The object of my invention is to provide an amusement device of the foregoing character, which will be simple and inexpensive of manufacture, and which will be instructive and attractive in appearance and operation.

With the foregoing and other objects in view, my invention consists of the new and useful details of construction, arrangement and combination of parts, described herein, illustrated in the annexed drawings, and pointed out specifically in the appended claims.

In the accompanying drawings, wherein the preferred embodiment of my invention is shown, like reference characters refer to like or corresponding parts throughout the several views.

Figure 1 is a front elevation of the mechanical toy of my invention. Fig. 2 is a detail perspective view of the hopper member. Fig. 3 is also a detail perspective view of the opening and closing device for the hopper outlet. Fig. 4 is a side elevation of my mechanical toy. Fig. 5 is a detail perspective view of the car body and endgate therefor, shown in their assembled relation. Fig. 6 is a detail perspective view of the endgate for the car.

Referring now to the drawings, numeral 1 designates a pair of upright standards, and numerals 2 a pair of rear upright standards, which standards comprise a framework upon which inclined track bed 3 is mounted, the rear standards being of greater length than the forward standards.

Numerals 28 designates a rectangular base frame upon which the superstructure is mounted.

Track bed 3 is preferably formed of a single plate, and is equipped with a pair of parallel rails 4 and with upstanding flanges

on the outer edges. Rails 4 are of a uniform height, while flanges 5 are provided with a triangular projection 27 on each of their lower ends, terminating at the forward standards 1. This projection is for a purpose which will be hereinafter fully explained.

Rear standards 2 are provided with extensions above the inclined track, to which is mounted a hopper 6, which may be of any desired shape having a tapered bottom portion with a single outlet opening 7 therein. Opening 7 is positioned midway between the track rails 4 and slightly thereabove, and an opening and closing device is mounted to operate thereunder.

Numerals 8 designates an angle plate mounted to cross shaft 9, which shaft is pivoted by brackets 10, or similar means, to standards 2.

Numerals 11 designate pendant weights hung to crank arms 12 secured to cross shaft 9.

Angle plate 8 is adapted to be normally positioned directly under opening 7 in the hopper, weights 11 on crank arms 12 normally holding the cross shaft and angle plate in that position.

On track bed 3, I provide a car such as 13 having wheels adapted to travel between rails 4 and flanges 5 on the track bed. A weighted cable 14 is attached to the rear end of car 13 and passes over pulley 16 mounted on cross shaft 17 on the upper end of inclined track bed 3. Cross shaft 17 is mounted to rotate in bearing means provided on the upper edge of flanges 5, and pulleys 18 are fixed thereto on each end. Pulleys 18 are each provided on their outer faces with cranks 19, to which automatons 20 may be attached to be actuated thereby. Endless cables 21 are carried about pulleys 18 and pulleys 22 mounted to flagstaffs 23. Flagstaffs 23 are mounted to the frame-work, and flags may be mounted to the cables, to move upward and downward with the cables.

Car 13 is provided with a vertical endgate 24 carried in slide-ways 25 on the forward end of the car, slots 26 allowing the endgate to raise a portion of the height of the car. Endgate 24 is provided with projecting ends on each side of the car 13, which ends are adapted to just clear the upper edge of flanges 5 of the track bed, when the car is in place on the track, and when the

endgate is at its lowest or closed position on the car. It will be readily seen that, as the car descends on track bed 3, when endgate 24 reaches triangular projection 27, projection 27 will raise the endgate upward to allow the contents of the car to be dumped. Numerals 29 designate stops which engage the wheels of the car and prevent further travel downward.

10 In operation, I fill the hopper 6 with sand, or similar material, angle plate 8 normally closing the opening in the bottom. Car 13, being empty, will be drawn upward along the track by weight 15 on cable 14. As the 15 rear end of the car comes into contact with crank arms 12, cross shaft 9 will be rotated in bearings 10 and angle plate 8 actuated out from under opening 7 in hopper 6. Sand from the hopper will then feed out 20 of hole 7 into car 13. When sufficient sand has fed into the car to overcome the weight 15, car 13 will descend along track rails 4, and angle plate 8 will swing back into its 25 normal position under the mouth of hopper 6 by the actuation of weights 11. When the car reaches the lower end of track 4, endgate 24 of the car will be actuated upward by projections 27, and the sand will be dumped. Weight 15 will immediately draw 30 the car upward, and the same operations will be repeated continuously until the sand in the hopper has become exhausted.

It will be readily seen that, as pulley 16 is 35 revolved during the ascent or descent of car 14, likewise pulleys 18, automatons 20, and flags 30 on cables 21 will be actuated automatically therewith.

While I have herein described and illus-

trated the preferred embodiment of my invention, I do not wish to be limited strictly 40 to the construction shown, as it is obvious that the details of arrangement and combination may be varied in many ways, without departing from the spirit of my invention.

Having thus described my invention, what 45 I claim is:—

1. In a mechanical toy, the combination of a frame-work, an inclined track mounted on said frame-work, a shaft mounted across the upper end of said track, a pulley in the center of said shaft, a car on said track, a cable attached to said car and carried over the pulley on the shaft, a weight on the rear end of said cable to normally draw the car upward along the track, pulleys on each end 55 of said shaft, flagstaffs mounted above the inclined track, pulleys on the upper ends of the flagstaffs, and cables carrying flags trained over the pulleys on the ends of the shaft and the pulleys on the flagstaffs, substantially as described.

2. In a mechanical toy, a frame-work, an inclined track thereon, a car adapted to travel on said track, and means for dumping said car comprising a vertically sliding 65 endgate on the car having projecting end portions, and a flange on each side of the track providing up-raised portions adapted to engage the under side of the projecting ends of the endgate to actuate said endgate 70 upward, substantially as described.

JOHN W. COLGLAZIER.
